UNITED STATES PATENT OFFICE.

WILLIAM C. BREITENBACH, OF PHILADELPHIA, PENNSYLVANIA.

DESIGN FOR A GAME-BOARD.

SPECIFICATION forming part of Design No. 30,395, dated March 28, 1899.

Application filed February 25, 1899. Serial No. 706,886. Term of patent 7 years.

To all whom it may concern:

Be it known that I, WILLIAM C. BREITENBACH, a citizen of the United States, and a resident of Philadelphia, in the county of Philadelphia and State of Pennsylvania, have invented a certain new and useful Design for a Game-Board; and I do declare the following to be a full, clear, and exact description of the invention, such as will enable others skilled in the art to which it appertains to make and use the same, reference being had to the accompanying drawings, which form a part of this specification.

Figure 1 of the drawings is a plan view of the game-board. Fig. 2 is a section on line $x x$, Fig. 1.

This invention has relation to a certain new and original design for game-boards.

The leading feature of the design consists in a game-board having therein seventeen apertures, sixteen of which are arranged in radial lines about the seventeenth aperture, which is at the center of the board, said aper-

ture being also arranged on the sides of three concentric parallelograms, each of the two outer of which has its sides bisected by the angles of the next smaller parallelogram. The central aperture is surrounded by a star figure, from the points of which radiate the lines upon which the apertures are radially disposed. The inner and outer parallelograms have parallel sides, and the intermediate parallelogram has its sides bisected by the angles of the inner parallelogram, and its angles in turn bisect the sides of the outer parallelogram.

What I claim is—

The design for a game-board substantially as herein shown and described.

In testimony whereof I affix my signature in presence of two witnesses.

WILLIAM C. BREITENBACH.

Witnesses:

GEORGE H. PARMELEE,
GEO. M. ANDERSON.
